UNITED STATES PATENT OFFICE.

DONALD W. McGEE, OF CHICAGO, ILLINOIS.

LUBRICATOR.

Application filed January 21, 1925. Serial No. 3,780.

My invention belongs to that general class of devices known as lubricators, and relates more particularly to a lubricating device adapted to force or feed under pressure a measured quantity of lubricant to any required number of points from a common source of supply. More particularly the same relates to a lubricating device particularly designed and adapted for use on automobiles or the like, although its use is not limited to the dispensing of a lubricant, the same being applicable for the dispensing of other fluids for other purposes than lubrication. The invention has among its objects the production of a device of the kind described which is simple, compact, positive, reliable, durable, efficient and satisfactory. It has particularly as an object the production of a device that will deliver a measured quantity of material to a desired number of points from a central point, and in which the delivery to any point is not reduced owing to any resistance in the lines. If there is any resistance or delay of the device to function promptly in the manner intended, such is disclosed by the delay of the foot pedal in returning, whereby a correction of the difficulty may be made. Many other objects and advantages of the construction herein shown and described will be obvious to those skilled in the art from the disclosures herein given.

To this end my invention consists in the novel construction, arrangement and combination of parts herein shown and described, and more particularly pointed out in the claims.

In the drawings, wherein like reference characters indicate like or corresponding parts:

Fig. 1 is a perspective view illustrating one embodiment of my invention;

Fig. 2 is a vertical sectional view taken substantially on line 2—2 of Fig. 3;

Fig. 3 is a transverse sectional view 45 through the device;

Fig. 4 is a sectional view taken substantially on line 4—4 of Fig. 3;

Fig. 5 is a cross-sectional view of my preferred form of apparatus taken substantially on line 5—5 of Fig. 6;

Fig. 6 is a sectional view taken substantially on line 6—6 of Fig. 5;

Fig. 7 is a sectional view through a portion of the device taken substantially on line 55 7—7 of Fig. 5; and

Fig. 8 is a detail view of one of the feed plungers.

Referring to the drawings, in which the preferred embodiment of my invention is shown, there is provided a container of 60 suitable size, shape and material, and made up of the desired number of parts secured together in any suitable manner. The container shown consists of the base or bottom portion 1 provided with a cooperating portion 2 forming the side walls and cover, thereby with the base 1 providing a chamber 3 for containing lubricant or any other fluid which it is desired to dispense. The base portion 1 or bottom is shown provided with 65 an upstanding portion 4 which is of sufficient length so that it extends up to and through the top portion 2 as indicated at 5, the parts being secured together by a nut 6 or equivalent means. The parts 1 and 2 75 are made to fit together more or less closely to prevent leakage, gaskets (not shown) however, being provided between the parts if so desired. In the construction shown in Figures 2, 3 and 4 the part 5 is formed 80 tubular as indicated at 7 and communicates with a bore or well 8 through the duct 9. Projecting into the bore 7 is a plunger 10, a plunger 11 being also arranged in the bore 8. The part 5 is shown provided with 85 a port 12 through which oil may flow into the space between the plungers 10 and 11, the operation being such, as hereinafter described, that when plunger 10 is depressed the oil between the plungers will cause the 90 plunger 11 to be elevated and vice versa when plunger 11 is depressed, as hereinafter described, the same will cause the plunger 10 to be raised or retrieved. As shown the plunger 11 is provided with a projecting 95 portion 15, on which is arranged a plate 16. Arranged between the plate 16 and a bracket 18 on part 5 is a spring 17, or the equivalent of the desired tension, which tends to force the plunger 11 to the position shown in Fig. 100 4 and normally maintain it in that position. The base is also provided with portions 20 of the desired size, depending upon the number of feed plungers employed, twelve being shown in the figures (see Fig. 3).

There is provided a plurality of ducts or wells 21 and 22, and these extend to the exterior of the casing as indicated at 23 and 24, or in an equivalent manner. These are discharge ports from which extend the pip- 110

ing or conduits 25, each terminating at a desired point to provide for the delivery of a lubricant or other fluid to where desired. The number depends, of course, on the number of desired delivery points. As shown, 5 ports or ducts 26 and 27 connect the ducts 21 and 22 with the chamber 3. Carried by the plate 16 are the supplemental or feed plungers 28, the same being preferably secured to the plate in any suitable manner, as for example, by means of a threaded extending portion 29 and nuts 30. The 10 plungers 28 may be of the same length or of varied lengths, as will be hereinafter described, and they may be of the same or varied diameters.

The container is shown provided with a drain port which is normally closed by the drain plug 31 and with a filling inlet which 20 is normally closed by the plug 33. The container may be mounted in place in any suitable manner, as shown, by a bracket 34 connected integrally with the base or other part, or otherwise connected therewith.

25 A variation in construction and the preferred one is shown in Figs. 5, 6 and 7 in which 1'-2' represent the container which, in this case, is arranged with a plurality, two being shown, of plunger containers 4', and 30 5' represents a tubular member securing parts 1 and 2 together. Part 5' also forms a carrier for the plunger 10', as well as a guide for the spring and plunger plate 16'. As shown two plungers 11' are employed in this 35 construction, the same being arranged to cooperate with the plate 16' mentioned. In this case, the spring 17' is arranged about the pipe 5' between the plate 16' and a stop plate 14 secured to 5'. The plungers 28' are secured to the plate and control the feeding 40 of the lubricant from the container, as hereinafter described. The plunger casing 5' is provided with one or more ports 12', and the extended portion 13 on the plate 16' is provided also with ports 19. I have illustrated 45 in detail in Fig. 8 a simple method of securing the plungers 28' to the plate 16', so that especially close machine work and laying out is not essential, as slight variation may be 50 compensated for in assembling. Fig. 7 also shows a variation in sizes of the plungers. This feature is shown in dotted lines in Figure 2 at the left-hand side and I have also shown in this figure in dotted lines how the 55 port may be varied in its location.

When the device is installed on an automobile, it is ordinarily placed below the floor boards 35 (see Fig. 1) and adjacent the driver's seat so that it may be conveniently 60 operated. This, however, is merely as a matter of preference and not an essential location. It also has the convenience of being a more or less central location in the case of an automobile installation.

65 Assuming that the device is installed on

an automobile with the pipes 25 connected with various points to be lubricated, as for example the shackle bolts, brake rods, steering knuckles, etc., flexible connections being used wherever found necessary, and the container filled with a lubricant such as an oil of the desired grade, the apparatus is ready for lubricating at any desired time. When it is desired to lubricate, the operator depresses the plunger rod 10, and its movement 70 is transmitted to the plunger 11 through the oil between the two plungers so that plunger or piston 11 is raised, compressing spring 17, carrying plate 16 and plungers 28 upwardly. Obviously, a very little pressure on the foot 75 plunger will be required to compress a comparatively heavy spring 17 since the plunger 11 is operated hydrostatically and is of greater area than the plunger 10. In fact, a comparatively slight pressure on the plunger 80 rod 10 is sufficient to compress a spring 17, exerting several hundred pounds pressure against the plate 16. As the several plungers 28 are raised, a measured quantity of oil 85 flows below the plungers 28, the quantity depending upon the length of the plunger and the cross-sectional area of the same. When the foot pedal is released, the spring 17 tends to carry the plate 16 downwardly, returning 90 the plunger 11 to its normal position, at the same time hydrostatically raising the plunger 10. The oil in the ducts 21 and 22 is forced outwardly through the ducts 23 and 24 into the pipes 25, the ports 26 and 27 being closed by the downward movement of 95 the plungers. Obviously, varying the size of any of the plungers 28 or location of the ports 26 or 27 will vary the discharge so that it is possible to deliver a desired measured charge of lubricant to any desired point. 100

The operation of the preferred construction shown in Figs. 5, 6 and 7 is substantially the same. As the plunger rod 10' is operated, its movement causes an actuation of the plungers 11', thereby raising plate 16' 105 and compressing the spring 17', as well as lifting the plungers 28'. Upon releasing the plunger rod 10', the spring 17' returns the parts, causing a discharge of lubricant from 110 container to where desired. This construction is particularly satisfactory, inasmuch as the parts are so arranged that warping, twisting or binding between the parts is 115 eliminated. The assembly is very convenient. For different types of cars, or for installations with a different number of lubricating points, it is only necessary to select a base or bottom portion 1 having the desired number of outlets and feed plungers, 120 all of the other parts of the apparatus being similar for different sizes. It is possible, however, to take one with an excess number of outlets, remove the plungers 28' in any of them and plug up the unnecessary outlets so 125 that a base with a large number of ports is 130

- also suitable for installation where a less number is required without any machine work or drilling of extra outlets. This plugging of any of the outlets and removal of the plungers is simple and there will be no leakage inasmuch as there is no pressure in the container except in the wells in which plungers are operating. This feature is of great advantage for the devices are applicable in installations where one or more oil lines are to be taken off without requiring a special model of device for each particular installation. In other words, the device is practically standardized for all installations.
- 15 The apparatus shown in Figs. 1 to 4 is applicable for twelve or less lubricating points, while that shown in Figs. 5 to 7 is applicable for twenty-four or less, and the device may be designed for as many lubricating points 20 as found necessary.

The plungers 28 or 28' in effect serve four purposes: to force, to measure, and to suck in a fresh charge, and as they remain down, when not in operation or normally, they 25 close both the inlet and outlet ports, preventing oil from entering the lines or escaping from them.

The apparatus has numerous advantages. A very little pressure on the foot plunger 30 will exert a tremendous pressure on a clogged line. One push only on the foot plunger is required to lubricate all points, although, of course, the foot plunger may be operated more than once if desired. A 35 single impulse on the foot plunger is transformed into a continuous pressure until all clogged lines are free and all points lubricated. The pressure on the foot plunger, the distance through which it is exerted, 40 and the time consumed by the operator are the same for any operation of the device, regardless of the resistance in the lines. Check valves or domes are not required in order to maintain a continuous pressure or 45 to measure the oil, thereby preventing loss of pressure and inaccurate measurement. However, check valves if desired may be employed in any line to prevent the oil from being drawn back from a bearing. When 50 the foot plunger reaches the top, the operator knows that the car has been lubricated, as it will not return to its original position until all points are oiled, and if it does not return promptly, the operator then knows that the car is not being lubricated frequently enough. Due to the continuous pressure, the natural movements of the chassis parts, while driving, assist materially in freeing frozen surfaces. It will be particularly noted that in this season the greater 55 the resistance in any oil line, the greater is the pressure applied on the oil in that line; so that, therefore, if one line should become clogged, all the pressure is applied 60 on that line and is continuous until the ob-

struction is removed. As before mentioned, the proportions of the parts may be varied so as to vary the amount of oil or pressure to any desired point relative any other point.

The device is arranged for the desired 70 number of discharge ports, and the portions 4 may be constructed around the plunger 11 as indicated at 40 and the dotted line in Fig. 3. Obviously, the parts 1 and 2 may be secured together in any equivalent manner 75 to that shown, and the parts 5 and 4 arranged at any desired point on the base. This depends to a large extent on the number of feed plungers required in the device. In some cases it is desired to locate the 80 plunger 10 at one side rather than centrally. While only one spring 17 is shown, there may obviously be any desired number.

Having thus described my invention, it is obvious that various immaterial modifications may be made in the same without departing from the spirit of my invention; hence I do not wish to be understood as limiting myself to the exact form, construction, arrangement and combination of parts 90 herein shown and described or uses mentioned.

What I claim as new and desire to secure by Letters Patent is:

1. In a device of the kind described and 95 in combination, a container provided with a plurality of discharge ports, conduits communicating with said discharge ports, a plunger arranged in each conduit, and means for controlling said plungers, said means comprising a spring common to said plungers and operative to actuate the same to force fluid through said conduits, and manually operable means for controlling said spring and simultaneously moving the plungers to 100 permit the passage of fluid from the container into said conduits comprising a fluid-actuated plunger, and controlling means 105 therefor.

2. In a device of the character described 110 and in combination, a container provided with a plurality of discharge ports, conduits communicating with said discharge ports, a plunger arranged in each conduit, a plate having connection with all of said plungers, 115 a spring bearing against said plate, a fluid actuated plunger having connection with the plate, a tubular upstanding portion in the container having communication with the well of the fluid actuated plunger, and 120 a manually operated plunger movable in the tubular upstanding portion whereby to force the fluid in said upstanding portion into the well of the fluid actuated plunger to impart movement to the same for compressing said 125 spring and retrieving the plungers.

In testimony whereof, I have hereunto signed my name.

DONALD W. McGEE.
